CLAIM

The ornamental design for a beverage container cap, as shown and described.

DESCRIPTION

FIG. 1 is an isometric view of a beverage container cap showing the design.

FIG. 2 is a side elevation view of the beverage container cap of FIG. 1.

FIG. 3 is another side elevation view of the beverage container cap of FIG. 1.

FIG. 4 is another side elevation view of the beverage container cap of FIG. 1.

FIG. 5 is another side elevation view of the beverage container cap of FIG. 1.

FIG. 6 is a top plan view of the beverage container cap of FIG. 1.

FIG. 7 is a bottom plan view of the beverage container cap of FIG. 1; and,

FIG. 8 is another isometric view of the beverage container cap of FIG. 1.

1 Claim, 5 Drawing Sheets
